UNITED STATES PATENT OFFICE.

JAMES R. KEARNEY, OF KANSAS CITY, MISSOURI.

GROUND ANCHOR.

Application filed April 24 1922. Serial No. 556,276.

Figure 1 is a view illustrating the manner of using my ground anchor.

Figure 2 is a top plan view of the anchor.

Figure 2^a is a detail view of the movable 5 jaws employed on the anchor.

Figure 2^b is a detail view of a spring for holding the movable jaws closed.

Figure 3 is a side elevational view of the anchor.

10 Figure 4 is an end elevational view.

Figure 5 is an enlarged section taken on the line 5—5 of Fig. 3.

Figure 6 is a partial view of the anchor rod.

15 Figure 7 is a side elevational view of an implement employed in placing the anchor on the rod.

This invention relates to a new and useful improvement in ground anchors such as are 20 employed in connection with rods to which guy ropes, cables, etc., may be connected.

In using ground anchors of the type herein contemplated, an opening, such as indicated at A in the drawing, is preferably 25 formed in the ground by a posthole digger or other implement and at an angle to the horizontal, as shown. The guy rod B is then driven through the ground so that its inner threaded end projects into the opening A, 30 as shown in Figure 1, after which the ground anchor is engaged with the threaded end of the guy rod and said guy rod turned so as to seat its threaded end into the anchor. The guy rod B may have an eye C formed 35 on its outer end, or said eye may be detachably secured to the outer end and to which eye is intended to be secured the end of the cable or rope to be anchored.

In the drawings, 1 indicates the body portion 40 of the ground anchor which is preferably formed with an upper convex surface, above which extend ribs 2, the height of said ribs increasing towards the center of the anchor where they are conjoined to 45 the ribs 3 and 4, which with the web wall 5 form a box-like structure having a recess or slot 6 in the shelf-like wall thereof.

7 indicates a pivot pin passing through 50 this box-like structure, on which are pivotally mounted jaws 8, said jaws having flaring walls 9 at their outer ends and registering semi-cylindrical threaded openings 10 in their adjacent faces with which registers a 55 threaded opening 11 in the body wall of the anchor, as shown in Figures 3 and 4.

The underside of the anchor is preferably formed with diagonally arranged reinforcing ribs 12 which are conjoined to the centrally located boss 13, in which the threaded opening 11, before referred to, is arranged. 60

One end of the body web of the anchor is provided with a perforation 15 and a notch 16. 17 indicates an implement, preferably in the form of an elongated metal rod having one end 18 flattened to form a tamping tool, 65 while its outer end is provided with a cap piece 19 having a projection 20 and a groove 21 which are designed to engage the ground anchor by cooperating with the hole 15 and recess 16 thereof, such engagement enabling 70 the operator to insert the ground anchor in hole A and engage the threaded end of the guy rod with the threaded recesses of the spring-held jaws.

Assuming that the hole A is dug and the 75 guy rod B is arranged in position, as indicated, a ground anchor is fitted on the end of the rod 17 and introduced into the opening A, the operator forcing the anchor upon the end of the rod until the threaded portion of the rod is forced between the jaws which are yieldingly held together by a spring 23, detailed in Figure 2^b and the threads on the rod engage the semicylindrical registering openings in the spring-held 85 jaws. When such engagement is effected, the rod 17 is disengaged from the ground anchor. The converging ribs 2 will help in guiding the end of the rod B in between the jaws and into the recess formed by the overhanging shelf. 90

Should the ground anchor not be connected to the rod, a hook 22 on the underside of the cap on rod 17, can be employed to engage the opening 15 in the ground anchor and withdraw it from the hole to be again arranged in position on the placing rod for engagement with the guy rod. The ground anchor having been engaged between the jaws, the guy rod is now rotated so as to 100 force its threaded end beyond the jaws and into the threaded opening in the body web of the anchor, thus fixing the anchor on the end of the rod.

When the anchor is so fixed, the earth is 105 replaced in the opening A and preferably tamped by the widened end 18 of the placing rod.

If at any time, it is desired to remove the guy rod, it may be unscrewed and with- 110

drawn, and the anchor may be left in the ground, or may be dug up, if desired.

The boxlike structure which houses in the movable jaws and their spring, serves to 5 protect these moving parts from the entrance of dirt or other foreign particles which might interfere with their operation at the time that the ground anchor is being introduced into position on the guy rod.

10 After the guy rod is engaged with the movable jaws, then dirt packed behind said jaws and in the space between the jaws and the housing serves to hold said jaws fixed, and, hence, is not objectionable.

15 When the rod is screwed into the anchor, it passes from engagement with the threads of the movable jaws to the threads of the boss of the anchor plate, and hence has a solid threaded engagement with said plate. It is 20 obvious that the rod may be unscrewed from the plate at any time even though the anchor plate per se be abandoned.

What I claim is:

25 1. A ground anchor having a box-like projection extending from its upper side, and which is open at one end, and yielding guy rod attaching means housed within said box-like extension.

30 2. In a ground anchor, a guy rod, a body, a pivoted set of jaws mounted thereon for engagement with said guy rod, and means yieldingly holding said jaws in operative position.

35 3. A ground anchor comprising a body portion, and a pair of spring-held pivoted jaws mounted thereon and adapted to engage a guy rod.

40 4. A ground anchor comprising a body portion convex on its upper face and having converging reinforcing ribs for guiding a guy rod into a predetermined position, and

flexible means on the ground anchor for receiving said guy rod and adapted to hold the same in said predetermined position.

5. A ground anchor comprising a body 45 portion having a box-like housing on its upper side, a pair of spring-held jaws arranged in said housing for engagement with a guy rod, the contiguous faces of said jaws being provided with registering threaded semi-cylindrical recesses, and said body portion being provided with a threaded opening in alignment with a recess between said jaws. 50

6. In combination, a ground anchor, the body of which is provided with a threaded opening, a threaded guy rod, means for guiding said rod to a desired position over said opening when the rod is moved transversely of the opening, said means also serving to hold said rod when so positioned. 55

7. In combination, a ground anchor comprising an anchor plate having a threaded opening, a guy rod adapted for threaded engagement with and disengagement from said anchor plate, and threaded yielding means for guiding said guy rod and holding it in position to engage said threaded opening. 60

8. A ground anchor comprising a rod having threads on an end thereof, a plate 70 having an opening therein, threaded means associated with said plate and adapted to engage with the threads on said rod, said plate being adapted to be positioned in an opening in the earth and said rod being driven 75 through undisturbed earth at an angle to meet said plate whereby said plate may be drawn up against undisturbed earth in said opening.

In testimony whereof I hereunto affix my 80 signature this 10th day of April, 1922.

JAMES R. KEARNEY.
